PORTABLE HOIST

Orville Schultz, Buffalo, N. Y.

Application August 3, 1950, Serial No. 11,581

Term of patent 7 years

(Cl. D41—1)

To all whom it may concern:

Be it known that I, Orville Schultz, a citizen of the United States, residing at Buffalo, in the county of Erie and State of New York, have invented a new, original, and ornamental Design for a Portable Hoist, of which the following is a specification, reference being had to the accompanying drawing, forming a part thereof.

The figure is a perspective view of the portable hoist embodying my new design.

The dominant features of my design reside in the portions shown in full lines.

I claim:

The ornamental design for a portable hoist, substantially as shown and described.

ORVILLE SCHULTZ.
